TOWEL CABINET

Application filed March 13, 1930. Serial No. 435,480.

In the operation of a cabinet of the continuous web type, difficulty has been experienced in making suitable disposition of the loose soiled portion of the towel when the end of the supply is reached, the user has pulled the last wiping length over the delivery feed device, and the primary towel winding operation has been completed.

Unless the cabinet is equipped with some means for making suitable disposition of this soiled section of the towel, as by a supplemental winding, it will depend below the cabinet in an unsightly manner and children or persons not familiar with cabinets of this type might use the soiled portion again and use might be continued to such an extent as to cause infection.

It is desirable, therefore, that provision be made so that when the clean supply of towel is exhausted, the used portion will be drawn up to a position where it will be practically invisible and cannot be readily used again.

The object of my invention therefore is to provide a simple, inexpensive attachment for a standard type of cabinet, which, without adding materially to the expense of construction of the cabinet, will positively and expeditiously withdraw the soiled length of towel from view at a predetermined point in the use of the cabinet, as when the user has withdrawn the last wiping length of web.

A further object is to provide an attachment made automatically operative at a certain time as when the supply of clean towel is exhausted, for winding up and withdrawing the soiled portion from view.

Other objects of the invention will appear from the following detailed description.

The invention consists generally of various constructions and combinations, all as herein-after described, and particularly pointed out in the claims.

In the accompanying drawings forming part of this specification,

Figure 1 is a vertical sectional view through a towel cabinet embodying my invention showing the supply of clean towel ready for delivery to the user;

Figure 2 is a similar view showing the position of the parts when the mechanism

has been released to withdraw the soiled portion of the towel from view, the normal position being indicated by dotted lines;

Figure 3 is a front elevation of the cabinet with the door in its open position;

Figure 4 is a longitudinal sectional view through the towel winding roller;

Figure 5 is a detail view partially in section showing the normal position of the controlling mechanism when the cabinet is in use;

Figure 6 is a detail view showing the position assumed by the control yoke and the releasing lever when the supply of towel is exhausted;

Figure 7 is a detail view showing the locking dog and the releasing lever in their normal position;

Figure 8 is a similar view showing the position of the parts when the lever has been moved to its releasing position and the dog disengaging from the sleeve of the roll; and

Figure 9 is a sectional view on the line 9—9 of Figure 7.

In the drawings, 2 represents the outer section or casing of the cabinet having a front door 3 provided with the usual mirror 4. Within this casing is a supporting frame 5 for the operating mechanism of the cabinet.

This frame is pivotally supported at 6 on each side of the cabinet, and is adapted to swing forwardly on its pivots through the open front of the cabinet when the door is in open position, being normally held within the cabinet by a spring actuated lock device 7.

The lower portion of the frame is adapted to support a supply of clean towel 8. A feed roll 9 having a suitable roughened surface is mounted in the frame above the clean towel supply preferably near the front of the cabinet and a similar roll 10 is arranged in parallel relation with the roll 9 preferably in the rear thereof and slightly above its level.

The usual driving connection 11 is provided between these rolls for simultaneous operation thereof. A guard 12 preferably extends between the rolls preventing possible contamination of the roll 9 from the periphery of the roll 10 which contacts with the soiled towel. A suitable lock device 13 on the outside of the cabinet is adapted to be

manipulated by the user for the purpose of releasing the rolls and allowing one complete revolution of each roll to deliver a predetermined length of clean towel and wind up a corresponding length of soiled towel. A pinch roll 14 is preferably mounted in guide slots 15 in the inner frame of the cabinet and is so positioned with respect to the feed roll 9 that downward pull of the towel web 10 stretched from the supply over the pinch roll and thence downwardly through an opening 16 in the bottom of the cabinet, will tend to draw the pinch roll against the surface of the feed roll with sufficient pressure so that both of the rolls will be driven by frictional contact of the towel web with the feed roll and the pressure of the pinch roll thereon.

The towel web, after being passed down through the opening in the bottom of the cabinet, is extended up through a passage 17 in the rear of the inner frame and after contacting with suitable guiding and tensioning means 18 and 19, is wrapped around a take up roll 20 that is slidable in slots 21 in the inner frame and adapted to rest by gravity upon the surface of the winding feed roll 10. The normal operation of roll 10 performs the primary winding of the towel.

The user standing in front of the cabinet 30 and manipulating the lock device 13 to release the rolls, will pull on the towel and deliver for this use a predetermined length of the clean web and this operation will be repeated until the end of the supply is reached.

I will now proceed to explain in detail my invention which forms the subject matter of this case, for automatically retracting or withdrawing the soiled portion of the towel 40 from view when the supply is exhausted, or whenever the winding mechanism is released, and effecting a supplemental winding of the soiled towel.

Turning now to Figure 4, the take up feed roll is in the form of a cylinder having heads 22 and 23. An annular flange 24 is provided at one end outside the head 23 and overlaps the hub 25 of a sprocket wheel 26 that is rigidly secured to the end of the roll shaft 50 27 by suitable means such as the pin 28. The driving connection 11 extends from the sprocket 26 to a similar sprocket on the delivery feed roll 9. The ends of the shaft 27 are journaled in suitable bearings 29 in the side walls of the frame and one end of a helical spring 30 coiled loosely around the shaft 27 is secured at 31 to the head 22 and the other end of said spring is suitably secured to the shaft at 32 by being preferably thrust into a 60 socket therein. The convolutions of the spring are loose on the shaft so that the roll may be revolved a limited distance independently of the supporting shaft and the spring placed under tension to return the 65 roll to its normal position when released.

This is an idle movement the reverse of its forward winding revolution. The head 22 has a flange 33 provided with a series of internally formed notches 34 spaced apart around the inner surface of the flange. I have shown in Figure 7, three of these notches made preferably by recessing the inwardly turned edge of the flange and these notches are equally spaced apart and there may be any suitable number of them. A disk 35 is secured on the shaft between the bearing 29 therefor and the head 22 and a locking dog or detent 36 is pivoted at 37 intermediate its ends to the inner face of the disk 35 and this detent is provided with a lug 38 that is adapted to enter any one of the notches 34 and temporarily lock the roll. A spring 39 normally holds this detent in its locking position, the notches and detent forming in effect a ratchet for the roll, allowing it to be revolved backwardly with the shaft stationary against the tension of the spring for a limited distance, but locking the roll to the shaft to revolve forwardly with it in the other direction in the normal operation of the cabinet. As indicated in Figure 1, the rolls 9 and 10 normally revolve counter-clockwise in the operation of the cabinet and the take up roll 20 revolves clockwise to wind the soiled towel thereon. The manner of mounting the roll 10 on the shaft 27 as explained above, permits a limited idle rotation of this roll in a backward or clockwise direction for the purpose of putting the spring 30 under tension and setting the roll so that when the end of the clean web is reached, as will be hereinafter explained in detail, the roll 10 will be released and the tension or energy stored in the spring on the shaft will revolve the roll rapidly in its normal forward direction of movement and immediately pull the loose depending portion of the soiled towel into the cabinet or up against the lower wall thereof in a position where it cannot be used, and will be practically invisible. Any suitable mechanism may be employed in connection with the roll for temporarily locking it when it is set by idle rotation in a clockwise direction and for tripping the locking means when a predetermined point in the delivery of the towel is reached. I prefer, however, to provide the means which I will now describe in detail as it is a simple, positive mechanism for accomplishing the desired result.

The detent has an outer end 40 between the flange of the head 22 and the disk 35 and a lever 41 has an end 42 adapted to be moved into the path of the part 40 of the detent and tilt it on its pivot to disengage its lug from the notch of the roll 10. The lever 41 preferably has an offset 43 therein projecting through a slot 44 in the side wall of the frame and pivoted at 45 to the lower portion of the frame. A guide strap 46 is pref-

erably provided on the frame to prevent outward movement of the lever in the slot but allowing it to oscillate freely therein. The lever 41 has an extension 47 below its pivot terminating in a fork with an upper arm 48 and a lower arm 49.

A yoke 50 has a U-shaped central portion provided with a weight 51 and is journaled at its ends in the side walls of the frame 10 and the end adjacent the lever 41 is provided with a cam 52 which, when the lever is in its normal upright position, as indicated in Figure 5, will engage the arm 48 and swing the lever 41 to its release position as indicated by full lines in said figure. The yoke in this position will bear on the web of clean towel, an extension 53 being provided at the middle portion of the yoke for this purpose.

The inner section or frame of the cabinet 20 preferably has a slot 54 in the rear wall thereof adapted to receive the extension 53 when the yoke drops down to a horizontal position as indicated by full lines in Figure 2. When this movement of the yoke takes 25 place, the cam 52 will swing down and engage the arm 49 of the lever 41 and thereupon the upper end of the lever 41 will be swung forwardly to the position indicated by dotted lines in Figure 5. It will then be in the 30 path of the detent 36 and will swing it to the position indicated by full lines in Figure 8 when the roll has revolved a sufficient distance to bring the detent in contact with the end of the lever. This will release the 35 roll and the spring therein having been previously put under tension by revolution of the roll in a clockwise direction, the movement of the detent to its release position will allow the power of the spring to revolve the 40 roll and effect a supplemental winding up of the loose depending loop of soiled towel from the position indicated by dotted lines in Figure 2, to that indicated by full lines in the same figure. When the soiled towel 45 has been drawn up in this way, the web will be practically concealed from view and cannot be grasped and used again. In this way the winding device not only adds to the appearance of the cabinet, withdrawing the 50 soiled web from view, but also prevents possible infection of anyone by the use of a soiled section of towel.

The winding roll is usually revolved in its clockwise direction the desired distance 55 to put the spring therein under tension by the attendant grasping the soiled end of the towel before removing the roll from the cabinet and pulling downwardly thereon, thereby drawing a few lengths of the web out of the 60 cabinet until the roll is revolved idly a sufficient distance in the opposite direction to its normal movement to insure sufficient energy being stored up in the helical spring to revolve the roll in the opposite direction 65 when the locking dog is released. It will be

clearly understood from an inspection of Figure 2, that when the attendant grasps the soiled towel and pulls downwardly thereon, sufficient pressure will be transmitted through the convolutions of the soiled towel 70 to the roll 10 to revolve it in a clockwise direction until the actuating spring is put under the desired tension. If preferred, or should the soiled towel be removed from the cabinet without first putting the helical 75 spring under tension, the attendant may reach through the open front of the cabinet, grasp the roll 10 and revolve it toward the front of the cabinet until the spring 30 is sufficiently tensioned. Generally, however, it 80 is preferable to obtain this adjustment of the roll by pulling downwardly on the web of soiled towel before the roll thereof is removed from the cabinet.

As plainly shown in Figure 1, the oscillating yoke is held in an upright position between the upwardly extending web from the towel supply and the depending portion that is carried through the bottom of the cabinet and the yoke will remain in this 85 position until the end of the towel supply is reached when as shown plainly in Figure 2, it will drop by gravity to the horizontal full line position causing the cam 52 thereon to actuate the lever 41 as explained above. This yoke is swung out through the front of the cabinet when the door is open to depend below it in an idle position having during its movement swung the lever 41 to its idle position thereby permitting backward movement of the winding roll against the tension of its spring.

I prefer to provide flat steel springs 55 in the rear of the inner section or frame to prevent the clean towel roll, when it is comparatively small and nearly exhausted, from crawling out under the weighted yoke, the tension of these springs tending to hold the rolled web toward the front of the cabinet. These springs are preferably held by their 105 tension within the frame of the cabinet and may be readily removed whenever desired.

In loading the cabinet the yoke normally hanging vertically below the cabinet, will be raised to a position within the cabinet to 110 rest against the towel web when it is carried up around the pinch roll. When the web has been stretched down through the cabinet to form the loop of the desired length and thence to the take up roll in the upper rear 115 portion, the door may then be closed and the weighted yoke will be held in this vertical position until the towel supply is exhausted.

In various ways the details of construction herein shown and described may be modified 120 and still be within the scope of my invention.

I claim as my invention:

1. In a towel cabinet, towel delivery and winding instrumentalities having a driving connection between them for simultaneous 125

- movement, said winding instrumentality having a reverse movement independent of said delivery instrumentality and provided with a forward actuating means energized by such movement, a detent for holding said winding instrumentality in its reversed position, and means adapted to be released at a predetermined period in the use of the cabinet for tripping said detent.
2. In a towel cabinet a soiled towel winding roll, and means for operating it, a take up roll whereon the web of soiled towel may be wound for contact with said winding roll, to be actuated thereby, said winding roll normally having a counter-clockwise revolving movement to operate said take up roll and also having a limited revolution in a clockwise direction, means put under tension by such clockwise movement of said roll, a detent for locking said winding roll and holding said means under tension, and mechanism for tripping said detent at a predetermined period in the use of the cabinet to allow a rapid winding operation of said winding roll whereby a soiled normally exposed loop of towel web may be wound on said take up roll and concealed from view.
3. In a towel cabinet, delivery and winding towel rolls having a driving connection between them for driving said winding rolls from said delivery roll, a support for a clean towel supply wherefrom a web of towel may be stretched to said delivery roll, a take up roll whereto the web of soiled towel may be stretched from said delivery roll, said winding roll having a limited revolution in the opposite direction to its normal winding movement, a spring put under tension by such opposite movement of said roll, a detent for holding said roll with said spring under tension, and mechanism automatically operative at a predetermined period in the use of the cabinet when movement of said delivery roll has ceased for releasing said detent and allowing said spring to revolve said winding roll, for the purpose specified.
4. In a towel cabinet, a soiled towel winding roll, a take up roll whereon the web of soiled towel may be wound with its convolutions in contact with said winding roll, said winding roll having means whereby it may be revolved in one direction to operate said take up roll and also revolve in a reverse direction, means put under tension by the revolution of said roll in said reverse direction to return it to its normal position when released, a detent for locking said roll in its adjusted position with said means under tension, a lever for tripping said detent and a yoke having means for moving said lever to its release position at a predetermined period in the use of the cabinet.
5. In a towel cabinet, a soiled towel winding roll, a take up roll whereon the web of soiled towel may be wound with its convolutions in contact with said winding roll, said winding roll having a revolving movement in one direction to operate said take up roll and also having a limited movement in the reverse direction, means whereby said winding roll may be normally driven to wind up the soiled towel in said take up roll, means put under tension by the revolution of said winding roll in said reverse direction for also operating said take up roll, a detent for normally locking said winding roll during its reverse movement against the pressure of said tension means and mechanism for tripping said detent to allow the rapid winding movement of said roll and the withdrawal of the exposed towel within the cabinet.
6. In a towel cabinet, a soiled towel winding roll and a driving connection therefor, a take up roll whereon the soiled towel may be wound with its convolutions in contact with said winding roll, said winding roll having a revolving movement in one direction by the operation of said driving connections and also having freedom of revolution in the opposite direction, a spring put under tension by the revolution of said roll in said opposite direction, a detent for normally locking said roll in its adjusted position with said spring under tension, a lever adapted to be moved into the path of said detent for tripping the same and releasing said roll, means normally in an upright position within the cabinet and adapted to drop by gravity to a horizontal position and move said lever to a release position at a predetermined period in the use of the cabinet.
7. In a towel cabinet, a pivoted member normally held substantially upright, a soiled towel winding roll having a forward winding movement and a reverse idle movement, a take up roll whereon the soiled towel may be wound during the forward movement of said winding roll, a forward driving mechanism for said roll, means energized during the reverse idle movement of said winding roll, a detent for holding said winding roll against the tension of said means, and a detent releasing device actuated by said pivoted member when it is allowed to fall to a substantially horizontal position.
8. The combination with a revolving member having a forward soiled towel primary winding movement and a reverse idle movement, and towel delivery mechanism for operating said member forwardly, of a spring put under tension by such reverse movement, a detent for holding said member and said spring under tension, and a releasing device automatically operative under certain conditions of towel delivery for tripping said detent, whereby said member will be revolved forwardly to effect a supplemental soiled towel winding while said delivery mechanism is stationary.
9. A towel cabinet having an open front and

- 5 a support for a clean towel supply, a member pivoted between said support and open front and substantially upright in its working position, a towel delivery means whereto the web of towel may be stretched from said supply in the rear of said pivoted member and from said delivery means downwardly in front of said pivoted member, a soiled towel winding means whereto the web of 10 towel may be stretched in the rear of said supply, mechanism for operating said towel winding means to effect a primary winding of the soiled towel, said winding means having a reverse or backward movement and means put under tension by such movement, a 15 detent for normally holding said winding means when moved backwardly and a detent tripping device actuated by the movement of said pivoted member to release said winding means and effect a supplemental winding of the soiled towel.
10. A towel cabinet having an open front, a weighted member normally supported in a substantially upright position, a cam mounted on said member, a lever having a forked end to receive said cam, a soiled towel winding roll, a take up roll whereon the soiled towel may be wound for contact with said winding roll to effect a primary winding, 25 said winding roll having a reverse or backward movement and a spring put under tension by such backward movement, a detent for normally locking said winding roll against the tension of said spring, said lever being normally out of the path of said detent and having one of its arms in the path of said cam to move said lever into the path of said detent when said weighted member is released from its upright position.
- 30 11. A towel cabinet having an open front and a support for a clean towel supply, a member pivotally supported between said support and open front and substantially upright in its normal position, towel delivery and winding rolls mounted in said cabinet and having a driving connection between them, said delivery roll being above said 35 towel support whereby the web of clean towel may be stretched upwardly thereto on the inner side of said pivoted member and thence downwardly on the outer side thereof to form a loop below the cabinet, a take up roll whereon the web of soiled towel may be wound from said loop, said winding roll contacting with the soiled towel and having a movement in one direction with said delivery roll to effect the primary winding of the soiled towel on said take up roll and having also a limited movement in a reverse direction when said 45 delivery roll is stationary, means put under tension by the reverse movement of said winding roll, a detent for holding said roll against the tension of said means and a releasing device for said detent actuated by the inward movement of said pivoted member from its

upright position to permit the supplemental winding action of said winding roll.

12. A towel cabinet having an open front and a support for a clean towel supply, a pivoted member mounted in said cabinet adjacent said open front, towel delivery and winding rolls mounted in said cabinet and having a driving connection between them, said delivery roll being so positioned with respect to said towel support that a web of clean towel may be stretched thereto and thence downwardly through the bottom of said cabinet to form a loop below the same, a take up roll whereto the depending loop of towel may be carried in the rear of said support, said take up roll being supported adjacent said winding roll and actuated thereby to effect a primary winding, said winding roll having an independent backward or reverse movement, a spring put under tension by the reverse movement of said winding roll to actuate said roll and effect a supplemental winding action, a detent for said roll, a releasing lever having a forked end and said pivoted member having a cam thereon positioned to engage the arms of said fork alternately and oscillate said lever to its releasing and non-releasing positions, whereby when said pivoted member swings to a predetermined point in said cabinet, said winding roll will be released and a supplemental winding of said take up roll effected.

13. In a towel cabinet, a winding member having a movement in one direction to effect a primary winding of the soiled towel and also having a limited reverse idle movement, means made operative by such idle movement to again operate said member in said one direction and effect a supplemental winding operation, a ratchet mechanism for holding said member during its reverse movement against the power of the means for effecting said supplemental winding, and means for releasing said member at a predetermined period to effect such supplemental winding operation.

14. The combination with means operated by the towel user for delivering a length of clean towel and simultaneously winding up a length of soiled towel, of mechanism automatically wound up by a pull on the clean toweling and which automatically becomes operative when the clean towel supply is exhausted and delivery by the user ceases for effecting a supplemental operation of said winding means to wind the loose end of the towel.

15. The combination with means operated by the towel user for delivering a length of clean towel and simultaneously winding up a length of soiled towel, of means normally in contact with a downwardly hanging portion of the towel web and by it held from operation but becoming operative when said

hanging portion of the clean supply becomes exhausted, and spring mechanism released by the movement of said means for effecting a supplemental winding operation.

5 16. The combination with means for delivering a length of clean towel and winding up a length of soiled towel by a pull on the towel, of mechanism into which energy may be stored preliminary to such delivery for 10 effecting a supplemental movement of said winding means, and a device operative when the clean towel is exhausted for releasing said mechanism in which the energy has been stored to cause said supplemental winding 15 movement.

17. The combination with a revolving member having a forward soiled towel primary winding movement and a limited reverse idle movement, means energized by 20 such reverse movement for effecting a supplemental forward winding movement of said member, means for holding said member against the power of said energized means and a releasing device automatically operative under certain conditions of towel delivery for tripping said holding means whereby said member will be revolved forwardly to effect a supplemental winding 25 operation.

30 18. The combination with means for delivering a web of towel, of a device adapted to contact with a towel web which may be stretched to said delivering means, a roll whereon a web of soiled towel may be wound, 35 a winding member having a forward movement to revolve said roll, said winding member also having a limited reverse or backward movement and means made operative by such backward movement for effecting a 40 supplemental forward movement of said winding means, mechanism for temporarily restraining the supplemental forward movement of said winding means, and said device having a movement at a predetermined 45 period in the delivery of the towel for actuating said restraining means to release said winding member.

In witness whereof, I have hereunto set my hand this 5th day of March, 1930.

50 TRACY BROOKS TYLER.
